The Hoover Company, North Canton, Ohio, a
corporation of Ohio

Application August 20, 1938, Serial No. 225,873

21 Claims. (Cl. 62—119.5)

This invention relates to absorption refrigeration apparatus, and more particularly to an improved boiler-analyzer-solution-heat-exchanger assembly which is encased in insulation, and is provided with means for directing the products of combustion back over the outside of the boiler and upwardly over the analyzing column so as to utilize the heat from the products of combustion which would otherwise go to waste.

In an absorption refrigerating apparatus, the refrigerant is dissolved in an absorption liquid in an absorber and then expelled therefrom in a boiler by the application of heat. As the absorption liquid has a higher boiling point than the refrigerant, the refrigerant vapors can be separated from the absorption solution by the application of heat. But in spite of the difference in the boiling temperatures of the two mediums, some of the absorption solution passes off as vapor along with the refrigerant vapor. Unless some means is provided for separating the absorbent vapor from the refrigerant vapor, the operation as well as the efficiency of the machine is impaired.

One method of separating the two vapors is by the use of an analyzer, in which strong solution from the absorber is brought into contact with the hot mixture of vapors leaving the boiler under such conditions that the absorbent vapor is condensed and the heat of condensation is utilized to distill ammonia vapor from the strong solution as it returns to the boiler.

It is accordingly an object of this invention to provide a boiler-analyzer-solution-heat-exchanger assembly in which the heat contained in the products of combustion exhausted from the boiler is not only used to heat the outside of the boiler, but the analyzer column as well, and to provide a simple means of maintaining more uniform and exact temperature conditions in the analyzer.

In an absorption refrigerating apparatus of the type using an inert medium, the relative position and size of the various parts of the apparatus are somewhat critical, and stringent restrictions are imposed on the designer in applying such a machine to a domestic refrigerator cabinet.

It is accordingly another object of this invention to provide a compact boiler-analyzer-solution-heat-exchanger assembly which can be applied easily to a domestic refrigerator cabinet without taking up excessive space.

Since variations in room temperature and in the burner render it most difficult to maintain the analyzer temperature within the required critical range, my invention also makes provision for diluting the products of combustion with room air in accordance with the temperature conditions within the analyzer itself.

Other objects and advantages will become ap-

parent as the description proceeds, when taken in connection with the accompanying drawing in which the single figure diagrammatically shows a continuous absorption refrigerating apparatus with the boiler-analyzer-solution-heat-exchanger assembly shown in detail.

The refrigerating apparatus has a boiler 10, condenser 11, evaporator 12, motor 13, fan 14, and an absorber 15 connected in circuit by suitable conduits in a well known manner. The apparatus may be charged with ammonia as refrigerant, water as the absorbent medium, and an inert pressure equalizing medium, such as nitrogen. Heat is applied to the boiler 10 by means of a gas burner 16, and the products of combustion pass horizontally through the flue 17 into a jacket 18 surrounding the boiler 10 and the analyzer column 19, pass back over the outside of the boiler 10 and upwardly around the analyzing column 19 and out the stack, not shown.

The ammonia is absorbed in the absorbent liquid and the application of heat to the boiler 10 drives off the ammonia vapor from the absorbent liquid. This ammonia vapor and a small amount of absorbent vapor bubbles upwardly through the analyzing column 19 in counterflow to rich, relatively cool absorption solution returning from the absorber 15. As the rich, cool solution comes in contact with the hot vapors, the absorbent vapor is condensed and its heat of condensation serves to heat the rich solution and to liberate ammonia vapor therefrom. Baffle plates 20 are provided in the analyzer column so that the rich absorption solution flowing down over them can come in better contact with the rising hot vapors.

The refrigerant vapor and any absorbent vapor still mixed therewith flows upwardly through pipe 21 to rectifier 22 where the remainder of the absorption vapor condenses and flows backwardly to the boiler, and the ammonia vapor continues to the condenser 11 where it is liquefied and then flows to the evaporator 12 through pipe 23.

The weakened absorbent solution leaves the boiler 10 by pipe 24, passes through the inner coil of the solution heat exchanger 25, and is raised to the top of the absorber 15 by gas lift pump 26 which is operated by gas from the discharge side of the gas pump 14, flowing through pipe 27 into the gas lift pump 26 which is comparatively small in diameter so that the gas will lift slugs of absorption solution to the top of the absorber. The lean absorption solution flows downwardly through the absorber by gravity and returns to the boiler by way of solution reservoir 28, pipe 29, the outer pass of the solution heat exchanger 25, and analyzing column 19.

The fan 14 circulates an inert evaporation accelerating medium, such as nitrogen, in a closed circuit between the evaporator and absorber.

The inert gas leaving the discharge side of the pump by pipe 30, flows through the outer pass of gas heat exchanger 31, to the bottom of the evaporator by pipe 32 and upwardly therethrough in counterflow to liquid refrigerant entering the evaporator by pipe 23. The refrigerant diffuses into the inert medium producing refrigeration. The resulting mixture of inert medium and refrigerant vapor flows from the top of the evaporator through the inner pass of the gas heat exchanger 31 to the bottom of the absorber 15 and upwardly through the absorber in counterflow to the weak absorption solution. In the absorber the refrigerant vapor is absorbed out of the mixture, and the inert medium returns to the suction side of the fan 14.

A small dam 33 is provided in the upper tube of the evaporator to prevent liquid refrigerant from flowing down the gas circuit into the gas heat exchanger and a drain 34 leads from the bottom coil of the evaporator to the strong absorption solution pipe 29 so as to drain any residue or unevaporated solution away from the evaporator. A vent pipe 35 connects the top of pipe 24 to the top of the absorber so as to prevent a gas pocket forming in the solution heat exchanger.

The boiler-analyzer-solution-heat-exchanger assembly is embedded in insulation 36 and the solution heat exchanger surrounds the analyzing column as shown.

Since the solution heat exchanger surrounds the analyzing column, the flue surrounds the boiler and analyzer column and the whole assembly is embedded in insulation, a very compact unit is formed which takes up a minimum of space and in which a minimum amount of insulation conserves a maximum amount of heat. The compactness of the assembly is very advantageous when a machine of this type is applied to a domestic refrigerator since space is at a premium.

In order to provide a more accurate control of the analyzer temperature, a duct 37 leads into the space around the analyzer and is provided with a valve 38 operated by bellows motor 39 connected by tube 40 to thermostatic bulb 41 positioned in the top of the analyzing column. As the temperature of the analyzing column approaches the critical temperature of the refrigerant, it expands a fluid in the bulb 41 which operates the bellows motor 39 to open the valve 38 and allow air to enter through duct 37 and mix with the products of combustion flowing upwardly in the space about the analyzing column. Should this result in a lowering of the analyzer temperature toward the critical temperature of the absorbent vapor, the damper is closed slightly by the bellows to decrease the influx of room air to jacket 18.

Thus, it will be clear that the mixing of air with the products of combustion maintains the analyzing column at a uniform temperature so that it does not get so warm as to allow absorbent vapor to pass outwardly along with the refrigerant vapor, and neither is it permitted to become so cool as to condense refrigerant vapor. It also serves to prevent condensation of moisture out of the products of combustion by diluting the same with unsaturated room air.

From the foregoing it will be appreciated that I have provided a novel boiler-analyzer-solution-heat-exchanger assembly for an absorption refrigerating system which is more efficient and compact than any construction heretofore proposed, as well as one which is exceedingly simple in construction and operation, and one which is fully automatic.

While I have shown and described one modification of my invention, it is to be understood that this embodiment is to be taken as illustrative only and not in a limiting sense. I do not wish to be limited to the structure shown but to include all equivalent variations thereof except as limited by the scope of the claims.

I claim:

1. An absorption refrigerating apparatus comprising, a horizontally arranged boiler having an upwardly extending analyzer column associated therewith, means for heating said boiler by means of a combustible fuel and means for directing products of combustion over the exterior of the boiler and upwardly over the analyzing column.
2. An absorption refrigerating apparatus comprising, a boiler, an analyzer column associated therewith, means for heating said boiler by means of a combustible fuel, means for directing the products of combustion over the exterior of the boiler and analyzer column, and means for leading air into the products of combustion flowing over the analyzer column.
3. An absorption refrigerating apparatus comprising, a boiler, an analyzer column associated therewith, means for heating said boiler by means of a combustible fuel, means for directing the products of combustion over the exterior of the boiler and analyzer column, means for leading air into the products of combustion flowing over the analyzing column, and means for controlling said air supply.
4. An absorption refrigerating apparatus comprising, a boiler having an internal flue, an analyzer column associated therewith, means for heating said boiler by means of a combustible fuel burning in said internal flue, and means for leading the products of combustion over the exterior of the boiler and over the analyzing column.
5. An absorption refrigerating apparatus comprising, a boiler having an internal flue, an analyzer column associated therewith, means for heating said boiler by means of a combustible fuel burning in said internal flue, means for leading the products of combustion over the exterior of the boiler and over the analyzer column, and means for leading air into the products of combustion flowing over the analyzing column.
6. An absorption refrigerating apparatus comprising, a boiler having an internal flue, an analyzer column associated therewith, means for heating said boiler by means of a combustible fuel burning in said internal flue, means for leading the products of combustion over the exterior of the boiler and over the analyzing column, means for leading air into the products of combustion flowing over the analyzing column and means for controlling said air supply, said control means being responsive to analyzer temperature.
7. An absorption refrigerating apparatus comprising, a horizontally arranged boiler, an analyzer column associated therewith and extending vertically therefrom, and a solution heat exchanger located above said boiler and encircling said analyzing column to form a compact boiler-analyzer heat exchanger assembly, said assembly being embedded in insulation.
8. An absorption refrigerating apparatus comprising, a boiler, an analyzer column associated therewith, a solution heat exchanger encircling said analyzing column to form a boiler-analyzer heat exchanger assembly, said assembly being embedded in insulation, means for heating said

boiler by means of a combustible fuel, and means for directing the products of combustion over the boiler and analyzer column.

9. An absorption refrigerating apparatus comprising, a boiler, an analyzer column associated therewith, a solution heat exchanger encircling said analyzer column to form a boiler-analyzer heat exchanger assembly, said assembly being embedded in insulation, means for heating said boiler by means of combustible fuel, means for directing products of combustion over the boiler and analyzer column, means for leading air from the exterior of said insulation into the products of combustion flowing over said analyzing column, and means to control said air supply, said control means being responsive to analyzer temperature.

10. An absorption refrigerating apparatus comprising, a boiler-analyzer column assembly, said boiler having an internal flue, means for heating said boiler by means of combustible fuel burning in said flue, and a jacket surrounding said boiler-analyzer assembly, and communicating with said flue, whereby the products of combustion are led over the exterior of said boiler and analyzer.

11. An absorption refrigerating apparatus comprising, a boiler, an analyzer column associated with said boiler, a condenser, an evaporator, an absorber, means for circulating inert medium in a closed circuit between the evaporator and absorber and to utilize a portion of said inert medium to circulate the absorption solution in a closed circuit between the boiler and absorber, means to heat the boiler by means of combustible fuel, and a jacket surrounding said boiler and analyzing column whereby the products of combustion are led over the exterior of the boiler and analyzer column.

12. An absorption refrigerating apparatus comprising, a boiler, an analyzer column associated therewith, a condenser, an evaporator, an absorber, means to circulate inert medium in a closed circuit between the evaporator and absorber and to utilize a portion of said inert medium to circulate the absorption solution in a closed circuit between the boiler and absorber, means to heat the boiler by means of combustible fuel, a jacket surrounding said boiler and analyzing column whereby the products of combustion are led over the exterior of the boiler and analyzing column, and means to lead air into the products of combustion flowing over the analyzing column.

13. An absorption refrigerating apparatus comprising, a horizontal boiler, an analyzer extending upwardly therefrom and in open communication therewith, means for heating said boiler by means of a combustible fuel, means for leading absorption solution through said analyzer in counterflow to vapors flowing upwardly therethrough and means for leading the products of combustion into heat exchange relation with said analyzer.

14. An absorption refrigerating apparatus comprising, a boiler, an analyzer, means for heating said boiler by means of a combustible fuel, means for leading the products of combustion into heat exchange relation with said analyzer, and means for supplying atmospheric air into

the products of combustion flowing in heat exchange with the analyzer.

15. An absorption refrigerating apparatus comprising, a boiler, an analyzer, means for heating said boiler by means of a combustible fuel, means for leading the products of combustion into heat exchange relationship with said analyzer, means for supplying atmospheric air into the products of combustion flowing in heat exchange with the analyzer and means for controlling said air supply.

16. An absorption refrigerating apparatus comprising, a boiler, an analyzer, means for heating said boiler by means of a combustible fuel, means for leading the products of combustion into heat exchange relationship with said analyzer, means for supplying atmospheric air into the products of combustion flowing in heat exchange with the analyzer, and means for controlling said air supply, said control means being responsive to analyzer temperature.

17. An absorption refrigerating apparatus comprising, a boiler, an analyzer column associated therewith, means for heating said boiler by means of a combustible fuel, means for directing the products of combustion over the exterior of the boiler, and means for leading a mixture of atmospheric air and the products of combustion over the analyzer column.

18. An absorption refrigerating apparatus comprising, an elongated horizontally positioned boiler having a combustion flue extending horizontally therethrough, an analyzer column extending upwardly from said boiler at one end thereof, a gas burner positioned to discharge its flame into said flue at the analyzer end thereof, and means communicating with the discharge end of said flue for conducting flue gases into heat exchange with the exterior of said boiler and analyzer.

19. An absorption refrigerating apparatus comprising, a horizontal boiler, an analyzer column in open communication therewith, means for heating said boiler, means for leading absorption solution through said analyzer column in counterflow to vapors flowing therethrough, means for leading air over said analyzer column and means for controlling said last mentioned means.

20. An absorption refrigerating apparatus comprising, a horizontal boiler, an analyzer column in open communication therewith, means for heating said boiler, means for leading absorption solution through said analyzer column in counterflow to vapors flowing therethrough, means for leading air over said analyzer, and means for controlling said last mentioned means, said control means being responsive to the temperature of said analyzer column.

21. An absorption refrigerating apparatus comprising, a boiler normally filled with a solution of refrigerant in an absorbent, a jacket spaced from and surrounding said boiler, said boiler having an internal flue extending therethrough and communicating with said jacket at one end, and means for heating said boiler by means of a combustible fuel burning in said flue, whereby the products of combustion are led through said flue in one direction and reversely over the exterior of said boiler.

CURTIS C. COONS.
